(57) **CLAIM**

The ornamental design for a tag-loop carrier assembly, as shown and described.

DESCRIPTION

FIG. 1 is a front view of a tag-loop carrier assembly;
FIG. 2 is a back view thereof;
FIG. 3 is a top view thereof;
FIG. 4 is a bottom view thereof;
FIG. 5 is a side view thereof, as taken from the left side of FIG. 1;
FIG. 6 is a side view thereof; as taken from the right side of FIG. 1; and,
FIG. 7 is a sectional view as taken along lines 7-7 in FIG. 1.
The evenly spaced broken lines are for the purpose of illustrating environment and form no part of the claimed design. The dot-dash-dot broken away lines in the drawings indicate that any portion of the article beyond what is shown forms no part of the claimed design.
